UNITED STATES PATENT OFFICE.

WILLIAM RICHARD WHITE, OF BLOOMINGTON, ILLINOIS.

DESIGN FOR A GATE-LATCH.

SPECIFICATION forming part of Design No. 31,532, dated September 19, 1899.

Application filed August 24, 1899. Serial No. 728,377. Term of patent 14 years.

To all whom it may concern:

Be it known that I, WILLIAM RICHARD WHITE, a citizen of the United States, residing at Bloomington, in the county of McLean and State of Illinois, have invented and produced a new and original Design for a Gate-Latch, of which the following is a specification, reference being had to the accompanying drawings, forming part thereof.

Figure 1 is a perspective view of a gate-latch, showing my new design; and Fig. 2 is cross-section thereof on the line 2 2, Fig. 1.

The leading feature of my design consists of an upright body portion having end portions at right angles thereto, one of the end portions being connected to the body portion by a curved portion. Thus, referring more particularly to the drawings, A indicates the

upright body portion, and a a' the end portions thereof, which extend rearwardly at right angles therefrom, the end portion a being connected to the body portion by a curved portion a².

Having described my invention, what I claim as new, and desire to secure by Letters Patent, is—

The design for a gate-latch, substantially as herein shown and described.

In testimony whereof I have signed my name to this specification in the presence of two subscribing witnesses.

WILLIAM RICHARD WHITE.

Witnesses:

WALTER E. MAYNARD,
H. G. BINNS.
